[57] CLAIM

The ornamental design for a three-handled cup, as shown and described.

DESCRIPTION

FIG. 1 is a perspective view of a cup having three handles in accordance with a first preferred embodiment of my invention;

FIG. 2 is a bottom view of the three-handled cup illustrated in FIG. 1;

FIG. 3 is a view, from the left side, of the three-handled cup illustrated in FIG. 1;

FIG. 4 is a view, from the right side, of the three-handled cup illustrated in FIG. 1;

FIG. 5 is a top view of the three-handled cup illustrated in FIG. 1;

FIG. 6 is a front view of the three-handled cup illustrated in FIG. 1;

FIG. 7 is a back view of the three-handled cup illustrated in FIG. 1; and,

FIG. 8 is a cross-sectional view, through the center of the cup illustrated in FIG. 1.
